UNITED STATES PATENT OFFICE.

ROSE D. MURRAY, OF SEATTLE, WASHINGTON.

CLAMP SNAP.

Application filed February 14, 1923. Serial No. 618,915.

The invention is a snap with prongs projecting from its members by which it may be clamped to the goods instead of being sewn.

The object of the invention is to provide 5 a snap, the sections of which have points projecting from them that may be pushed through the goods and then bent over to clamp the snaps in place.

Another object of the invention is to provide 10 a snap that may instantly be applied to the goods.

And a further object of the invention is to provide a snap that may have sections in the shape of points punched from it 15 which sections may be bent back to clamp the snap to a piece of goods.

With these ends in view the invention embodies a snap the two sections of which are made with points projecting from them 20 which may be bent down to clamp the snaps to the goods.

Other features and advantages of the invention will appear from the following description taken in connection with the drawings, wherein:—

Figure 1 is a cross section through the upper section of the snap.

Figure 2 is a plan view of the upper section.

Figure 3 is a cross section of the lower section.

Figure 4 is a plan view of the lower section.

Figure 5 is a section showing the snaps on 35 goods and snapped together.

In the drawings I have shown my snap as it would be constructed wherein numeral 1 indicates the upper section and numeral 2 the lower section. The upper section may 40 be constructed as shown with an opening 3 in its center similar to that of a standard snap which receives the projection on the lower section; and points 4 projecting upward from its rim. These points may be 45 stamped out of the openings 5 in the body of the section as shown in Figure 2 or may be stamped from material on the outside of the section as shown in Figure 1 or they may be attached to the section in any desired manner. It is also understood that 50 these points may be of any desired shape or size and may project outward in any desired position. It will be seen that as the snap is placed against a piece of goods the

points 4 may be forced through the goods 55 and then bent downward against the body of the section so that the goods may be clamped between them and the section. It will also be seen that if desired these points may be made very narrow so that they may 60 be forced through the goods without cutting or breaking the threads.

The lower section shown in Figure 3 may be made as shown with points 7 similar to the points 4 of the upper section stamped 65 from the openings 8 in the body of the section as shown in Figure 4 or from additional material as indicated by the dotted lines 9. These points may also be of any suitable shape or length as described for 70 the points on the upper section.

The snaps may be furnished with the points projecting straight backward as shown.

It will be understood that changes may 75 be made in the construction without departing from the spirit of the invention. One of these changes may be in the number of points used as it is understood that any desired number of points may be used on either the upper or lower section. Another change may be in the design of the body of either of the sections as it is understood that the points may be used on snaps of any 80 design.

The construction will be readily understood from the foregoing description. To use the device it may be furnished as shown and it will be seen that as the points are placed against the goods they will force 90 their way through it and after the goods are firmly against the body of the section the points may be bent downward against the goods, thus binding the material between the inner surfaces of the prongs and the upper surface of the ridge formed by the edge of the snap from which the prongs project. It will be seen that they will positively hold the sections to the goods and it will also be seen that the snaps may be 95 stamped onto the goods by a small machine or other automatic means and it will therefore be possible to run a piece of goods through a machine and have it come out with the snaps in place.

Having thus fully described the invention, what I claim as new and desire to secure by Letters Patent, is:—

In a fastening device, two circular members, means for snapping one member into the other, one of the said members being flat and having points extending perpendicularly from its base, and the other of the said members having its body portion curved and having a curved flange around

its outer edge with points extending perpendicularly from the outer edge of the said flange, the inner edge of the said curved flange forming a binding ridge so that material may be gripped between it and the inner sides of the said points. 10

ROSE D. MURRAY.
